UNITED STATES PATENT OFFICE.

LEONARD E. WRAY, OF MINNEAPOLIS, MINNESOTA.

GRAIN-SPOUT MECHANISM.

1,349,354.

Specification of Letters Patent. Patented Aug. 10, 1920.

Application filed January 8, 1919. Serial No. 270,168.

To all whom it may concern:

Be it known that I, LEONARD E. WRAY, a citizen of the United States, residing at Minneapolis, in the county of Hennepin and 5 State of Minnesota, have invented certain new and useful improvements in Grain-Spout Mechanism; and I do hereby declare the following to be a full, clear, and exact description of the invention, such as will 10 enable others skilled in the art to which it appertains to make and use the same.

My present invention relates to grain spout mechanism, is in the nature of an improvement on my U. S. Letters Patent, 15 1,192,485, issued July 25, 1916, entitled "Flexible grain spout," and has for its object to provide means for transporting such spouts and bring the same into registration with overhead discharge spouts.

20 To the above end, generally stated, the invention consists of the novel devices and combinations of devices hereinafter described and defined in the claims.

In the accompanying drawings, which 25 illustrate the invention, like characters indicate like parts throughout the several views.

Referring to the drawings:

Figure 1 is a view of the invention in transverse section;

30 Fig. 2 is a fragmentary view partly in side elevation and partly in central vertical section;

Fig. 3 is a plan view;

Fig. 4 is a view partly in plan and partly 35 in horizontal section taken on the line 4—4 of Fig. 1, with some parts removed;

Fig. 5 is a view principally in rear elevation and partly in transverse vertical section taken on the line 5—5 of Fig. 2;

40 Fig. 6 is a detail view of the latch, with some parts sectioned on the line 6—6 of Fig. 2;

Fig. 7 is a detail view of one of the pivotal connections between the operating lever 45 and coupling sleeve with some parts sectioned on the line 7—7 of Fig. 3;

Fig. 8 is a detail view with some parts sectioned on the oblique line 8—8 of Fig. 2, on an enlarged scale; and

50 Fig. 9 is a detail view with some parts sectioned on the line 9—9 of Fig. 2.

The numeral 10 indicates the floor of an overhead storage bin or hopper having a plurality of openings 11, only one of which 55 is shown. Suspended from the ceiling of

the floor 10 by longitudinally spaced pairs of brackets 12, is a track 13 comprising a pair of rails, in the form of commercial angle bars and located under the openings 11, as shown in Fig. 1. 60

In registration with the opening 11, is a depending discharge spout 14 comprising upper and lower sections, the former of which is of cast metal and rigidly secured to the ceiling of the floor 10 by nut-equipped bolts 15. Each opening 11 will, of course, be provided with one of these spouts 14. The lower end of the upper section of the spout 14 is contracted and has formed in its outer face an endless channel 16 in which is 70 mounted a transversely divided collar 17. The upper end of the lower section of the spout 14 is telescoped onto the contracted lower end of the upper section thereof, a distance sufficient to receive the collar 17 and is 75 detachably secured thereto by screws 18. As shown, the lower section of the spout 14 is made from sheet metal and its lower end is contracted and of angular form.

80 Mounted on the track 13, is a truck, indicated as an entirety by the numeral 19, and comprising a rectangular frame 20 having at each corner a fixed axle 21 on which is journaled a flanged wheel 22. These flanged wheels 22 support the truck 19 on the track 85 13 for traveling movement thereon.

Suspended from the truck 19, is a flexible metallic distributing spout, indicated as an entirety by the numeral 23, and adapted to be transported by said truck to and from 90 positions under the discharge spouts 14. This distributing spout is designed for turning movement on its longitudinal axis and oscillatory movement from one side to the other of a vertical position, and comprises 95

an upper section 24, a lower section 25, and a head section 26 located between said upper and lower sections. The upper spout section 24 is in the form of a vertically disposed cylinder that closely fits within the 100 truck frame 20 and is rigidly secured thereto by rivets. This spout section 24 is of such length as to extend from the upper surface of the truck frame 20 to a point slightly below the track 13. The upper edge portion of the spout section 24 is made slightly flaring and, on its lower end, is a pair of upper and lower swivel rings 27, the former of

which is loose and the latter of which is rigidly secured by rivets to said spout sec- 105 110

tion and affords a support on which the upper swivel ring is free to turn.

The spout head 26 has flat sides and curved ends that are formed on arcs of the same circle and which head is suspended from the loose swivel ring 27 by an irregular shaped member 28, having a depending flange which closely fits within the upper end of said head and is riveted thereto. 5 This member 28 also has an upwardly projecting flange, which closely fits around the loose swivel ring 27 and is detachably secured thereto by screws 29. Obviously, the loose swivel ring 27 supports the spout head 10 26 from the upper spout section 24, with freedom for turning movement on a vertical axis.

The lower spout section 25 is suspended from the spout head 26 by two pairs of vertically disposed and diametrically opposite hinge straps 30, the pivots 31 of which are, as shown, in the form of nut-equipped bolts axially alined with the projected axis of the circle from which the ends of the spout head 25 26 are struck. The upper members of the hinge straps 30 are rigidly secured by rivets to the flat sides of the spout head 26 and the lower members thereof are likewise secured to the lower spout section 25.

30 The upper end portion of the lower spout section 25 is rectangular in cross section and the open lower portion of the spout head 26 projects therein. When this spout section 25 is hanging straight down, the upper edges of its end is only slightly above the lower edges of the end of the spout head 26. From the upper edges of the end of the lower spout section 25, the sides thereof are tapered upward to points above the pivots 31 and provided with bores through which said pivots project. By reference to Fig. 1, it will be noted that the inner ends of the pivots 31 also extend through bores in the sides of the spout head 26 and are mounted 35 in bearing plates 32 rigidly secured to the inner faces of the sides of said head. It will also be noted that the lower ends of the upper members of the hinge straps 30 are offset to embrace the upper ends of the lower members of said hinge straps and that their upper ends are bent horizontally outward to afford a pair of anchor lugs 33, the purpose of which will presently appear.

To close the open joints between the spout head 26 and lower spout section 25, I provide a pair of curved joint plates 34 that have close engagement with the curved ends of said head and are provided with flat segmental sides that also closely engage the flat side of said head and are pivoted on the pins 31. Beads 35 are formed on the lower edges of the joint plates 34 and frictionally engage the inner faces of the ends of the lower spout section 25 for alternate oscillatory movement therewith. Or, in other

words, when the lower spout section 25 is moved, we will say to the right, from a vertical position, the left-hand joint plate 34 will be moved therewith and, at which time, the right-hand joint plate remains stationary. A reverse movement of said lower spout section from a vertical position will cause the right-hand joint plate to move therewith and, at which time, the left-hand joint plate remains stationary. It will thus 75 be seen that the joint between the spout head 26 and lower spout section 25 is constantly kept closed to prevent the escape of grain and dust therethrough.

Coiled springs 36 are provided for yieldingly and independently holding the joint plates 34 in their uppermost positions. The inner ends of these springs 36 are attached to the anchor lugs 33 and their outer ends are anchored to horizontally disposed bolts 85 37 carried by U-shaped brackets 38 attached to the upper edge portions of the sides of the joint plates 34, as best shown in Fig. 2.

The lower end of the lower spout section 25 is of cylindrical form, and telescoped thereon is a spout extension 39. Rigidly secured to the upper end of the spout extension 39, is a wide collar 40, the upper end portion of which is curved outwardly and downwardly to afford an annular lock flange 41. To lock the spout extension 39 to the lower spout section 25, when in its uppermost position, I provide a pair of diametrically opposite latches 42. These latches 42 are gravity actuated and loosely suspended 90 from brackets 43 rigidly secured to the lower spout section 25. The hooked lower ends of the latches 42 normally hang in the path of movement of the lock flange 41 and, during the extreme upward movement of 105 the spout extension 39 on the lower spout section 25, said lock flange will engage the latches and cam the same out of its path of movement. As soon as the lock flange 41 has passed the hooked lower ends of the latches 42, said latches will swing inward, under the action of gravity, and when the spout extension 39 is released, said latches will engage the lock flange, and thereby support the spout extension 39 therefrom. The 110 intermediate portions of the latches 42 are bent to afford cam surfaces 44.

To release the lock flange 41 from the latches 42, the spout extension 39 is first moved upward to carry said lock flange 120 into engagement with the cam surfaces 44, and thereby swing the latches 42 outward of the path of movement of the lock flange 41. A quick downward movement of the spout extension 39 will then carry the lock flange 41 past the latches 42. Obviously, the lock flange 41 and flanges 42 permit free 125 turning movement of the spout extension 39 on the lower spout section 25. Stop pins 45 on the brackets 43 limit the up- 130

ward outward swinging movement of the latches 42.

To hold the loose swivel ring 27 on the fixed swivel ring 27, and thus prevent telescopic movement of the spout head 26 on the upper spout section 24, during the lifting movement of the spout extension 39 on the lower spout section 25, I rigidly secure to said upper spout section, just above the loose swivel ring 27, a plurality of circumferentially spaced blocks 46. Also to prevent the truck 19 from being displaced from the track 13, during this same movement of the spout extension 39, I secure to the side members of the truck frame 20 L-shaped retaining fingers 47, the horizontal portions of which extend outward under the rails of said track. These retaining fingers 47 are located sufficiently close to the rails of the track 13 to prevent the flanges of the truck wheels 22 from lifting above said rails, and thereby prevent displacement of the truck 19.

When the truck 19 is moved to position the upper spout section 24 in axial alignment with the discharge spout 14, said upper spout section is locked thereto and the joint therebetween is closed by a coupling sleeve 48. This coupling sleeve 48 is loosely telescoped into the upper spout section 24, and, when raised, telescopically receives the contracted lower end of the discharge spout 14, and thereby locks the distributing spout 23; and hence, the truck 19 under said discharge spout.

To raise and lower the coupling sleeve 48 within the upper spout section 24, I provide a lever 49, which comprises a pair of flat bars bolted together at their ends and bent outward at their intermediate portions to form a large ring which loosely surrounds the coupling sleeve 48. The ring portion of the lever 49 is secured to the coupling sleeve 48 by a pair of diametrically opposite pivots 50, in the form of nut-equipped bolts. These bolts 50, as shown, have large flat heads and are secured to the coupling sleeve 48 by inserting their bodies through central bores formed in flat pieces of metal 51 that are riveted to the outer faces of said coupling sleeve with the heads of said bolts between said sleeve and pieces of metal, as best shown in Fig. 7. By reference to Fig. 2, it will be noted that the seats 52 in the lever 49 for the bolts 50 are horizontally elongated to afford the necessary play of said bolts, during the raising and lowering movement of said lever. The rear end of the lever 49 is inserted between a pair of laterally spaced brackets 53 and fulcrumed thereto by a connecting bolt 54. The brackets 53 are rigidly secured to the truck frame 20 and to the upper spout section 24 by brace rod 55.

Secured in the outer or free end of the

lever 49, is a ring 56 to which is attached an operating cable 57, the lower end of which terminates within easy reach of an operator. The lever 49 is automatically raised; and hence, the coupling sleeve 48 is raised by a pair of coiled springs 58 that encircle a pair of bolts 59 having bifurcated heads and are compressed between said heads and the truck frame 20. These bolts 59 have their bifurcated heads pivoted to brackets 75 rigidly secured to the ring portion of the lever 49 rearward of the transverse center thereof. The bodies of the bolts 59 are guided by mounting the same in bores formed in the truck frame, and their lifting movement is limited, under the action of the springs 58, by placing on their lower ends nuts 61, which afford adjustable stops when lifted into engagement with the truck frame 20.

To lock the lever 49 down against the tension of the spring 58, I provide a gravity-actuated latch 62 intermediately pivoted off center at 63 to the front end of the truck frame 20, as shown in Fig. 6. On the upper end of the latch 62, is a detent 64 arranged to interlock with a lock notch 65 in the forward end portion of the lever 49, and thereby lock said lever to the truck frame 20. The lower end of the latch 62 is weighted at 66 and a stop 67 on the truck frame 20 limits the swinging movement of the upper end of said latch toward the lever 49. A cam surface 68 on the latch lever 62 is arranged to be engaged by the lever 49, when pulled down, to cam said latch out of the path of movement thereof and permit the detent 64 to enter the lock notch 65 under the action of gravity.

To release the latch 62 from the lever 49, it is only necessary to give said lever a slight downward pull, and thereby cause the same to move over the cam surface 68 and cam the lock detent 64 out of the lock notch 65. A quick release of the lever 49 will then permit the same to pass the latch and move upward out of engagement therewith. Obviously, when the truck 19 is positioned under one of the discharge spouts 14 and the lever 49 released, the upward movement of said lever, under the action of the springs 58, will telescope the coupling sleeve 48 onto the respective discharge spout. In positioning the truck 19, under a discharge spout 14, it is not necessary to have the upper spout section 24 in true alignment therewith. It is only necessary to have the truck 19 so positioned that, when the lever 49 is released, it will extend across the discharge spout 14 and bear thereagainst. In the released position of the lever 49, the same will extend in an inclined position with its free upper end portion bearing against the adjacent edge of the discharge spout 14, and acting as a cam surface thereon. With the

lever 49 thus positioned, the truck 19 may be pulled forward, by taking hold of the distributing spout, until the ring portion of said lever is substantially concentric with the discharge spout 14. In this position of the lever 49, the same is free from the discharge spout 14 and the springs 58 will lift said lever, and thereby telescope the coupling sleeve 48 onto said discharge spout.

10 In actual practice, a suitable gate or valve will be provided for closing the discharge spout 14. The spout extension 39 will also be provided with suitable hand holds by which the distributing spout may be manipulated to adjust the same, or cause the truck 19 to travel on the track 13.

What I claim is:

1. The combination with a fixed discharge spout, of an overhead track, a traveling truck on the track, a distributing spout carried by the truck, and a coupling sleeve carried by the truck and arranged for telescopic movement to connect the distributing spout to the discharge spout and position and hold the truck against movement on the track.

2. The combination with a discharge spout, of an overhead track located below the discharge spout, a traveling truck on the track, a distributing spout carried by the truck and arranged to be transported thereby to and from a position under the discharge spout, a coupling sleeve telescopically connected to the distributing spout, yielding means tending to project the coupling sleeve into registration with the discharge spout, and means for retracting the coupling sleeve.

3. The combination with a discharge spout, of an overhead track located below the discharge spout, a traveling truck on the track, a distributing spout carried by the truck and arranged to be transported thereby to and from a position under the discharge spout, a coupling sleeve telescopically connected to the distributing spout, a lever fulcrumed to the truck and intermediately pivoted to the coupling sleeve, springs tending to project the coupling sleeve into registration with the discharge spout, and a connection for operating the lever to retract the coupling sleeve.

4. The combination with a discharge spout, of an overhead track located below the discharge spout, a traveling truck on the track, a distributing spout carried by the truck and arranged to be transported thereby to and from a position under the discharge spout, a coupling sleeve telescopically connected to the distributing spout, a lever fulcrumed to the truck and intermediately pivoted to the coupling sleeve, springs tending to project the coupling sleeve into registration with the discharge spout, a connection for operating the lever to retract

the coupling sleeve, and a latch for holding the lever when the coupling sleeve is in a retracted position.

5. The combination with a discharge spout, of an overhead track located below the discharge spout, a traveling truck on the track, a distributing spout carried by the truck and arranged to be transported thereby to and from a position under the discharge spout, a coupling sleeve telescopically connected to the distributing spout, a lever fulcrumed to the truck and intermediately pivoted to the coupling sleeve, springs tending to project the coupling sleeve into registration with the discharge spout, a connection for operating the lever to retract the coupling sleeve, and an automatic latch for holding the lever when the coupling sleeve is in a retracted position.

6. The combination with a discharge spout, of an overhead track located below the discharge spout, a traveling truck on the track, a distributing spout carried by the truck and arranged to be transported thereby to and from a position under the discharge spout, a coupling sleeve telescopically connected to the distributing spout, a lever fulcrumed to the truck and intermediately pivoted to the coupling sleeve, a connection for operating the lever to retract the coupling sleeve, a spring compressed between the truck and lever and tending to move said lever into a position to project the coupling sleeve in registration with the discharge spout, and a latch for holding the lever when the coupling sleeve is in a retracted position.

7. The combination with a discharge spout, of an overhead track located below the discharge spout, a traveling truck on the track, a distributing spout carried by the truck and arranged to be transported thereby to and from a position under the discharge spout, a coupling sleeve telescopically connected to the distributing spout, a lever fulcrumed to the truck and having a ring-like intermediate portion encircling the distributing spout and pivoted to the coupling sleeve at diametrically opposite points, a pair of bolts pivoted to the intermediate portion of the lever and guided by the truck frame, coiled springs encircling the bolts and under strain to move the lever into position to project the coupling sleeve into registration with the discharge spout, a connection for operating the lever to retract the coupling sleeve, and a latch for holding the lever when the coupling sleeve is in a retracted position.

In testimony whereof I affix my signature in presence of two witnesses.

LEONARD E. WRAY.
